[57] CLAIM

The ornamental design for a face panel for a tape storage drawer, substantially as shown and described.

DESCRIPTION

FIG. 1 is a perspective view of a face panel for a tape storage drawer showing my design;

FIG. 2 is a top view thereof;

FIG. 3 is a bottom view thereof;

FIG. 4 is a front view thereof;

FIG. 5 is a rear view thereof;

FIG. 6 is a right side view thereof;

FIG. 7 is a left side view thereof.

The design is characterized by the combination of a generally wedge shaped body having a recess formed in its front, said recess in turn being provided with a plurality of horizontally extending rib members all as best illustrated in FIG. 1.
